APPARATUS FOR AMUSEMENT AND
INSTRUCTION IN AVIATION

Rafael Ponce Cortes, Mexico, D. F., Mexico

Application December 10, 1934, Serial No. 756,908
In Mexico December 22, 1933

6 Claims. (Cl. 35—12)

The object of my invention is to make those who use it feel some of the sensations of aeroplane flying, as well as to give them practical notions on the handling of modern aeroplanes, without any risk to the persons using my apparatus.

Fig. 1 is a plan view of the device.

Fig. 2 is an elevational view of the device shown in Fig. 1 with only two of its suspension arms.

Fig. 3 is an enlarged sectional view of a portion 10 of Fig. 2.

Fig. 4 is an elevational view of one of the arms per se.

Fig. 5 is an enlarged plan view of Fig. 3.

Fig. 6 is a sectional view taken on the line 6—6 15 of Fig. 5.

Fig. 7 is an enlarged sectional view of a portion of Fig. 3.

Fig. 8 is a sectional view taken on the line 8—8 20 of Fig. 7.

Fig. 9 is a sectional view of an airplane used in conjunction with this invention.

Fig. 10 is an enlarged detail view of a portion of Fig. 9.

Fig. 11 is an enlarged detail view, partly in section, of a portion of Fig. 10.

The apparatus for amusement and instruction in aviation, according to this invention, comprises, a circular gyrating tower which by means of ball-bearings rests on the axes of several wheels, which 30 in their turn, rest and run over a rail in a circle, fixed to the ground with radial ties that go up to the center of the said circle, being held at this point by means of an iron plate, which, at the same time that it joins them, contains a bearing 35 into which penetrates a hollow vertical axis fixed to the center of the base of the tower, and which has as an object that the wheels of the said tower should not derail. At the upper part of the tower there is a tank 6 of special shape with 40 a certain number of rack and spring valves 7, placed at the bottom of same, and these valves have an outlet tube alignable with the mouth of each of the counter-balance cylinders 4. At the lower part of the tower and resting on the floor 45 of same, there are two tanks 8, which are two, only to distribute the weight more evenly over the floor of the tower, and these tanks are filled up with water by means of a hose, before the apparatus is put in operation, and they also receive 50 the water that flows through pipe 37, which is inside the column 9; these tanks communicate one with the other and are connected to a centrifugal pump moved by a motor 10, which has as an object to lift the water from the lower 55 reservoirs 8, to the upper one 6. Another motor

39 moves, by means of a belt, another pulley, which is mounted on the shaft of the main transmission 11, which rests on bearings and has secured to it, a conical gear, by means of which it transmits power to another conical gear fixed 5 to a second shaft, which also rests on bearings and is placed transversally to the first one, and the second shaft has also fixed to it, the small wheel of a chain gear, which, by means of a chain, transmits power to the large wheel of the chain 10 gear, secured to a third shaft, which is also supported by bearings and placed below the floor of the tower, parallel to the second shaft and under it. This last shaft has near its bearings, at each end, an endless reversible screw or worm, which 15 gears with a gear wheel coupled to each of two of the lower wheels 13, on which the tower is supported, thus receiving power to drive the whole apparatus, at the start only, as the combined power of the motors of the planes, is sufficient to 20 give an ample impulse by means of the propellers. In this case, the drive is as described, but it can be of any kind suitable; the same motor (in due time) acts upon the irreversible endless screw 25 which is connected with the cog-wheel 14, which is coupled to the drum of the winch 15.

The tower before described has at its center an iron column 9, which serves to guide the two iron disks 17 and 40 or lower disk, and also contains 30 the pipe 37 which conducts the water that comes out of the counter-balance cylinders.

Disk 17 has in its center a box in the form of a ring where converge the outlets of some radial canals, and which serve to conduct the water that may come out from any of the counter-balances; this water is collected in the central box and flows by the conduit 31 to fall in the pipe 37 of column 9; the said disk 17 has oval perforations through which pass freely the lower end of the rack-bars of valves 7.

Under disk 17 there is another disk 40 supported by four connecting rods which articulate at the end of four levers 32, these levers turn on their longitudinal half and rest by means of a support upon the upper disk 17; at the other end 45 of the said levers, four cables are fixed, which meet at a certain distance, having as an object, that when they are pulled by means of lever 38, these cables will join together both disks 17 and 40.

The said disks 17 and 40 are suspended by means of two cables that pass through the groove of the pulleys 16, joining themselves later at an equalizing bar, which, in its longitudinal half has a perforation, where another cable is fixed, and 55

which, goes to wind up on the drum of winch 15. On the floor of the tower there is an iron plate on which are supported three levers, Y, Z, O. Lever O acts on the drum of a brake 33 by means of a transmission lining to enclose the said drum, braking therefore the two wheels 13, which, move together with the transmission where the drum 33 is coupled.

The lever Z acts on a conical clutch coupled 10 to the transmission shaft that is moved by motor 39; the clutch and the shaft have feather keys which allow the clutch to run along the shaft, to be coupled with the other part of the clutch that is fixed on the transmission, which is gearing 15 with two of the lower wheels 13.

The lever Y is supported at its lower end by a universal joint that allows it to be moved from right to left, and forward and backward, and at a certain height it is shaped in the form of a 20 ring, there, a ring is lodged, which at that place is secured to the lever by means of two bolts, placed diametrically and horizontally opposite; and in its turn, this ring fits into the slot of the 25 projecting hub of a pulley that goes inside the ring. This pulley, whose periphery is covered with leather, runs lengthwise on a shaft, which serves it as an axis and makes it to turn around with its rotating motion, by means of a feather key fitting a longitudinal slot in the said shaft, 30 which, in its turn, it gyrates supported by two bearings that can be moved a little, transversally, in relation to the shaft they support, because of a slot there is in them. This shaft has at an end, a universal joint that connects it to the section 35 of another shaft fixed to the frame of the winch by means of two bearings, having between the said bearings, an endless irreversible screw or worm of a single entrance, which gears with a spur wheel fixed by a feather key to the axis of 40 the drum of the winch. At the same height and forming a right angle with the shaft on which the leather covered pulley runs, the shaft of the main transmission 11, is placed, which, has at an end, a disk or plate 34, secured to it by a feather 45 key, therefore, it rotates with the main transmission. As the lever Y is placed vertically, the leather covered pulley is placed at the center of the said disk 34, therefore, in order to make the 50 worm turn to the right, the lever Y is moved to the right, pushing it simultaneously against the disk, with the result that the pulley comes in contact with the surface of the disk 34, which draws the pulley in its rotating motion, due to friction. As it may be understood all that is 55 needed to stop the endless screw, is to separate the pulley from the disk 34. To impress a reverse movement to the winch, the lever Y must be moved to the left.

Fig. 4 represents one of the arms or spokes which 60 rest on the upper part of the tower C by means of a steel axle 1, having an end that projects inside of the tower, two pulleys 2 grooved in their periphery, cables 3 run over the pulleys 2 and are connected at one extreme to the floor of the 65 tower, having suspended at their other extreme a cylindrical tank 4, which will be filled with water to serve as counterbalance to the aeroplane that is suspended at the other end of the said arm D, forming thus an intermotion lever.

70 Valves 7, Figs. 3, 7 and 8, consist of a stopcock but with the difference that this one, has on its head the section of a cog-wheel, which gears with a rack-bar which bar has a compression spring that compels it to be always at the lowest point 75 of its course, causing that the valve be always

closed, and it opens, only when pressure is applied upwards. By the rising ballast tank 4 on the rack-bar the spring is pressed together, causing the gear to gyrate, drawing the center of the valve up to a fourth of its turn, to allow the water to 5 pass.

Fig. 9 illustrates one of the aeroplanes, suspended at the outer extreme of each arm D, by means of a universal joint 5, Fig. 5, a little above its center of gravity. Fig. 10 represents in detail 10 the automatic control of the aeroplanes.

The aeroplanes have their movable rudders and are controlled the same way as or similar to those of the most widely used airplanes in modern warfare: the depth helm and the ailerons 15 being moved by a single control; being normally fixed since this helm is fixed in the direction of the circle that the aeroplanes describe while turning suspended at the end of the arms D; but this one differs from the other controls known, in 20 the fact that, this one has a special device 18, consisting in an intermotion lever or lever of the first kind 20 which can be placed in any position, but in this case it is near the rear of the airship, with one end toward the bottom of the plane, and the 25 other upwards, and it is supported by a bolt on which it can rotate. Near both of its ends it has two parallel pulley blocks secured to it, and at the end, below the lower blocks, it has a hole where a spring, fastened farther back in the 30 airship, is hooked, and it pulls its lower end towards the rear of the airplane. The lever has at its middle part, two iron or wooden guides. And as a part of the device, there is also inside the fuselage, Fig. 10, a panel 29, which is placed 35 more to the front part of the plane than the lever, having its upper border at about the same height as the upper part of the lever 20, and the said panel 29 has also two pulley blocks, and a little higher than the blocks, corresponding to each 40 one of them, it has also an iron or wooden guide. To complete the device 18, there are a control stick, two cables 21 of the hand control, two cables 19 and 24 of the automatic control, and also two cables 22 and 41, auxiliaries to the automatic control cables. One of the cables 21 of the hand control has an end tied below the pivot to the control stick, and the other cable 21 is tied above the pivot, then both free ends of these 45 cables, guided by blocks, run to the rear of the 50 plane, up to lever 20, which they reach transversally. There, they pass under and slide against the lower blocks of the said lever 20 and through the guides which this lever has at its 55 middle part. From there they pass over and slide on the upper blocks of lever 20, and there they issue, also in a transversal position to the lever, towards the rear of the airplane, where the free end of the cable that is tied to the control stick, below its pivot, is tied to the upper end of 60 the elevator horn, and the end of the other, is tied to the lower end of the elevator horn, thus crossing each other. Cable 19 of the automatic control, has a calculated length, so when the airship suspended at the end of the arm, is about at 65 the limit of its downward course, which is about a meter from the ground, it becomes taut. This cable is tied by one of its ends, at a proper height, corresponding to its length, to one of the columns between which the arm is placed; the other end 70 is passed through a tube inside the arm, and reaches the airplane at the point where it is suspended, and from there it is guided by pulley blocks toward the rear of the plane, and passes over and slides on the upper block of panel 29, 75

from where it runs to the lower end of lever 20, where it is secured at the hole which the lever has there. Cable 24 of the automatic control, is tied by one end, at a certain height, also corresponding to its length, to the column on which the arm rests, and its length is also determined like that of cable 19, so when the airship has reached the limit of its upward course, it becomes taut; its other end is passed like that of cable 19, through the pipe inside the arm, follows the same course in an identical way, and when it reaches the panel 29, it is passed over and slides on the lower block of the panel, to have its other end tied to the same hole at the lower end of lever 20, where 5 cable 19 was tied. Thus, both cables pull toward the front of the airship, in a direction opposite to the pull of the spring that is also hooked at the same hole of the lever where the cables 19 and 10 24 are tied. Cable 22, auxiliary to cable 19 of the automatic control, is secured by a grapple to the said cable 19, near the panel 29, and its other end, passing first through the upper guide of the said panel and through one of the upper ones of the lever 20, is also secured by a grapple, 15 to cable 21 of the hand control, whose end is tied to the upper end of the elevator horn. This device 18, operates in such a way, that when the control stick of the hand control is pulled backward, the airship suspended at the end of the 20 arm, will go up in proportion to the motion given to the control stick, as it pulls the cable 21 whose end is tied to the upper end of the elevator horn and raises the elevators, and then the airship goes up, because of its reaction, caused by the 25 effect of the wind on the elevators, just as it is done in all aeroplanes. When the control stick is pushed forward, the airship will go down in proportion to the movement given to the control stick, as it then pulls cable 21 of the hand control, 30 which is tied to the lower end of the elevator horn, and this lowers the elevators, and the aeroplane reacts, going down. As the control stick operates as it does in all aeroplanes, if it is moved to the right, the airship will bank to that side, 35 and if to the left, it will bank then to the left. When the airplane is near the limit of the upper course allowed to it, cable 24 of the automatic control becomes taut, because its length has been determined for the purpose, and it pulls 40 the lower end of lever 20, which, loosens the cables of the hand control just at the section that passes through the lever, and simultaneously, cable 24 as it becomes taut, pulls the auxiliary cable 41, and this one, in its turn pulls cable 21 45 of the hand control, at the point where they are joined by the grapple, and beyond that point where cable 21 has been loosened, and as cable 21 is tied to the lower end of the elevator horn, it lowers the elevators, and the airship goes down, 50 because it reacts due to the effect of the wind on the elevators, just as it acts in all aeroplanes. When the airship has come to the limit of distance from the ground, determined for it, which is about a meter from the ground, then, cable 19 55 of the automatic control and its auxiliary one 22, arranged as cables 24 and 41 are, pulls the cable 21 that has its end tied to the upper end of the elevator horn, which causes the elevators to be raised, and makes the aeroplane to go up for 60 the reasons stated.

The said aeroplanes have on their forward part and within the ogive which forms the prow of the fuselage a lining of threeply wood forming a megaphone, inside of which, passes 65 the transmission shaft which is coupled directly

to the electric motor 25 of the propeller that propels the aeroplane; on this same shaft a toothed wheel 26 is fixed, which on turning engages the lever 27 and produces a vibratory movement similar to that of the tongues of rattles, but with the difference that as this lever has its point of rest and of gyration on its longitudinal half and is constantly pushed by a spring 30 against the triangular teeth of the wheel 26, the other free end hits at each jump 10 from one tooth to the other, against the metallic disk 28 that is at the bottom of the megaphone, producing a noise that on being amplified by the megaphone resembles the noise produced by the explosions of gasoline motors. 15

Functioning of the apparatus in general

Once the motor 39 is started and the counter-balance tanks are filled, lever Y is pushed 20 making the winch 15 to roll up the cable 35, therefore making disks 17 and 40 go up, which puts in operation the upper disk 17 and the lower one 40, for two purposes: first, to lower all airplanes to about a meter from the ground, 25 and second, to accomplish the balancing of the counterbalance tanks that have excess of water, before a flight is started, and they are put in operation, as stated, by means of winch 15 and cable 35, which, raise all the counterbalances by 30 pushing them up, when at different heights they come in contact with the disk, by a piece that from the bottom of each tank, projects downwardly, for the purpose. When the disks have been raised to their proper and predetermined 35 height, in that position they will have lowered all the airships to about a meter from the ground, and then, the persons that are going to fly, can board the planes, aided by a small portable stair, and also with the disks in that position, the 40 outlet pipe 31 under disk 17, will fit into the entrance of pipe 37, which is inside the central column 9, and thus, the water that the counterbalance tanks may have in excess and which they discharge into the canals of disk 17, 45 runs through them and by pipe 31, into pipe 37, and from there, to tanks 8, from which it is again pumped up to upper tank 6, by pump and motor 10; and the unloading of the counterbalance tanks, which, due to having greater 50 weight are resting against or pressing down the disks, is operated after the new persons have boarded the plane, by pulling cables 36 by means of lever 38, and this will cause the lower disk 40, to be raised to join the upper one 17, with 55 the result that then disk 40, pushes up the automatic valves 7 under each completely filled tank, which will allow the water to flow till the balancing with the airplane is accomplished. In the mean time all the counter-balance tanks 60 that lack weight, have gone up by themselves to push their corresponding valve under the upper tank 6, and take in water till they are balanced. The lever 38, which joins disks 17 and 40, by pulling cables 36, can be any kind of 65 device for the purpose, but in this case it is a lever of the second kind, consisting in a bar which rests on, and is fixed at one end to, to the floor of the tower, and at about one third the distance from the end that is fixed on the 70 floor, it has secured to it, the ends of the four cables 36, which are to be pulled by it, the other end of the lever remaining altogether free, and when the disks are raised to their proper height, the lever in question 38, remains suspended by 75

the four cables 36, with its free end somewhat raised from the floor of the tower, and by pushing down that free end with the hand or the foot, it will pull the cables 36, and this will 5 make disk 40 to go up to join disk 17; now, if the weight of the persons that have boarded the plane should be greater than that of the liquid contained in the tank 4, the aeroplane will tend to go farther down and therefore will 10 lift the corresponding counter-balance tank higher up, making it push the rack-bar of valve 7 in the upper tank and on being opened it will let flow into the counter-balance tank the necessary water to equalize the weight, shutting itself 15 then by the pressure of the spring. If on the contrary the liquid contained in the counter-balance has a greater weight than that of the passengers, this tank will tend to go farther down and the rack-bar of its valve will hit on 20 the disk 40 therefore opening the said valve, producing an outlet for the water of the said tank, till the weight is balanced just as before; the excess of water discharged into the canals of disk 17 flowing through the pipe 37 of column 25 9, which pipe as it has been said before is connected to the lower tanks 8. This balancing is automatic and is accomplished in a very short time before the apparatus is set to gyrate. Now 30 the lever Y is pulled making the winch 15 to unroll the cable 35 which allows therefore disks 17 and 40 to go down by their own weight till they touch the floor of the tower, but before they get there, all the electric motors that 35 drive the propellers of the aeroplanes are put to work, but with a moderate speed, making them to take all their speed gradually to give the impression of the running of a real aviation motor; when all the motors are running the brake 33 will be loosened by means of lever 40 O, and pushing the lever Z, it will clutch the transmission that moves two of the lower wheels 13 making the tower gyrate till the aeroplanes take all their speed, which, impelled also at the 45 same time by their propellers will attain soon their maximum velocity, unclutching then with lever Z so that the tower may keep gyrating only by the impulse of the propellers of the aeroplanes, which will go up by themselves on account of the centrifugal force, only up to their 50 mid upper course; now if the person acting as pilot takes the control and pulls it toward himself, the aeroplane will go up with a speed in proportion to how much he has moved the control; if on the contrary he pushes the control forward, the aeroplane will descend with a velocity in proportion to the amplitude of the motion given to the said control. If the control is inclined to the right the aeroplane will 55 tilt to the right; if he inclines it to the left the aeroplane will bank to that side, and if he pushes the pedals to change direction, the aeroplane will respond, but rather continue on its normal route because the said rudder is simulated considering the circumference that the aeroplanes must describe necessarily their direction of flight cannot be controlled. When 60 the aeroplane almost reaches the limit of its upward course obeying the hand control, see 65 Fig. 10, the cable 19 of the automatic control becomes tense and pulls lever 20 loosening the cables of the hand control 21, allowing the cable 22 to move downward the elevator 23 the aeroplane recovering therefore its horizontal 70 flight. When the aeroplanes descend to almost 75

their lowest limit obeying the hand control 21, the cable 24 tightens acting on lever 20, but in this case the cable 41 is the one that makes go up the elevator, therefore, making the aeroplane recover its horizontal position of flight, no matter what the position of the hand control may be in the hand of the one that acts as pilot, on account of its automatic action. 5

When the time fixed for the flight comes to an end, the electric current that feeds the aeroplane motors is cut out, and by means of lever O the tower is braked little by little; simultaneously and by means of lever Y, the winch 15 will be made to work, which, on winding the cable, raises disks 17 and 40 as has been explained, causing the aeroplanes to come down till they come to about a meter from the ground regardless of the position in which they were when the current was cut out. When new persons board the airships, all the parts of the apparatus will be operated again as per description in the first paragraph of the description entitled "Functioning of the apparatus in general." 10 15 20 25

As it may be understood by the previous description, the public may operate these aeroplanes easily and at the same time that it is amused, it receives, without danger, instruction in aviation, as for additional security, each passenger will be secured to his seat by a strong leather strap similar to that which was used before in aviation and was generally called "scapulary". 30

I claim:

1. In an apparatus for amusement and instruction in aviation, a circular track mounted on the ground, a revolving base having wheels on the underside adapted to engage said track to permit said base to rotate, a tower mounted on the said base and comprising a central column and several columns mounted in spaced relation on said base, arms pivotally mounted on said several columns and having a greater portion extending from said tower, airplanes mounted on the outer extremities of said arms, pulleys mounted on the inner extremities of said arms, cables connected at one end to said base and extending over said pulleys, and ballast tanks mounted on the other end of said cables and adapted to control the pivoting of said arms. 35 40 45 50

2. In an apparatus for amusement and instruction in aviation, a circular track mounted on the ground, a revolving base having wheels on the underside adapted to engage said track to permit said base to rotate, a tower mounted on the said base and comprising a central column and several columns mounted in spaced relation on said base, arms pivotally mounted on said several columns and having a greater portion extending from said tower, airplanes mounted on the outer extremities of said arms, pulleys mounted on the inner extremities of said arms, cables connected at one end to said base and extending over said pulleys, and ballast tanks mounted on the other end of said cables and adapted to control the pivoting of said arms, and means for increasing the weight of said ballast tanks so that it will correspond with the combined weight of said airplane and the person in said airplane, comprising a lower reservoir full of water mounted on said base, an upper reservoir mounted in the top of said tower, a pipe line connecting said reservoirs, a centrifugal pump mounted on said base and in con- 55 60 65 70 75 80 85 90 95

junction with said pipe line and adapted to pump said water from said lower reservoir to said upper reservoir, several spring valves mounted on the under side of said upper reservoir, an outlet tube mounted on said valves, an opening in said ballast tanks adapted to align with said outlet tubes when said ballast tanks abut against said valves and opening them allowing water to flow from said upper reservoir into said ballast tanks.

3. In an apparatus for amusement and instruction in aviation, a circular track mounted on the ground, a revolving base having wheels on the underside adapted to engage said track to permit said base to rotate, a tower mounted on the said base and comprising a central column and several columns mounted in spaced relation on said base, arms pivotally mounted on said several columns and having a greater portion extending from said tower, airplanes mounted on the outer extremities of said arms, pulleys mounted on the inner extremities of said arms, cables connected at one end to said base and extending over said pulleys, ballast tanks mounted on the other end of said cables and adapted to control the pivoting of said arms, a spring valve mounted on the underside of said ballast tank, and a means for raising said ballast tanks to bring said airplanes to the ground comprising a motor mounted on said base, a winch mounted on said base, a shaft connecting said motor and said winch, pulleys mounted on said tower, a raising plate vertically slidably mounted on said central column and openings in said plate through which said spring valve may extend, and a means for causing said shaft to align with said motor to energize said winch to raise said ballast tanks and bring said airplanes to the ground.

4. In an apparatus for amusement and instruction in aviation, a circular track mounted on the ground, a revolving base having wheels on the underside adapted to engage said track to permit said base to rotate, a tower mounted on the said base and comprising a central column and several columns mounted in spaced relation on said base, arms pivotally mounted on said several columns and having a greater portion extending from said tower, airplanes mounted on the outer extremities of said arms, pulleys mounted on the inner extremities of said arms, cables connected at one end to said base and extending over said pulleys, ballast tanks mounted on the other end of said cables and adapted to control the pivoting of said arms, a spring valve mounted on the underside of said ballast tank, and a means for raising said ballast tanks to bring said airplanes to the ground comprising a motor mounted on said base, a winch mounted on said base, a shaft connecting said motor and said winch, pulleys mounted on said tower, a raising plate vertically slidably mounted on said central column and openings in said plate through which said spring valve may extend, and a means for causing said shaft to align with said motor to energize said winch to raise said ballast tanks and bring said airplanes to the ground, a means for decreasing the weight of said ballast tanks so that it will correspond with the combined weight of said airplane and the person in said airplane, comprising an outlet pipe in said central column and connected to said lower reservoir, canals radiating in spaced relation from the center of said raising plate and formed with openings on the inner end thereof, a box in the form of a ring mounted underneath said raising plate and just below said openings, a connecting pipe mounted on said box and adapted to connect said box and said outlet pipe, a pressure plate suspended below said raising plate, and a means for raising said pressure plate to open said spring valve to allow the water to flow from said ballast tanks in order to equalize the weight of said ballast tanks and said airplane, said latter mentioned means comprising a vertical rod mounted on said raising plate, a lever pivotally mounted intermediate of its end on said vertical rod, a connecting rod mounted on the outer end of said lever and connecting said lever and said pressure plate, cables mounted on the inner end of said lever, a pressure lever mounted on the floor and having the other end of the cables connected thereto in order to pivot said lever and pull up said pressure plate to abut against said valves to open them and allow the water to flow.

5. In an apparatus for amusement and instruction in aviation, a circular track mounted on the ground, a revolving base having wheels on the underside adapted to engage said track to permit said base to rotate, a tower mounted on the said base and comprising a central column and several columns mounted in spaced relation on said base, arms pivotally mounted on said several columns and having a greater portion extending from said tower, airplanes mounted on the outer extremities of said arms, pulleys mounted

6. In an apparatus for amusement and instruction in aviation, a circular track mounted on the ground, a revolving base having wheels on the underside adapted to engage said track to permit said base to rotate, a tower mounted on the said base and comprising a central column and several columns mounted in spaced relation on said base, arms pivotally mounted on said several columns and having a greater portion extending from said tower, airplanes mounted on the outer extremities of said arms, pulleys mounted

ed on the inner extremities of said arms, cables connected at one end to said base and extending over said pulleys, ballast tanks mounted on the other end of said cables and adapted to control the pivoting of said arms, a means adapted to rotate said base on said tracks, comprising a motor mounted on said base, a rod extending from said motor, a drive gear mounted on the end of said rod, wheel gears mounted on the same axle

with said wheels, a shaft supported below said base, worm gears mounted on the ends of said shaft and meshing with said wheel gears, a gear mounted on said shaft just below said drive gear, and a chain for connecting said drive gear and said gear to transmit the energy from said motor to said wheels to make the said base rotate. 5

RAFAEL PONCE CORTES.
